UNITED STATES PATENT OFFICE.

GEARY E. CARSON, OF ALBANY, NEW YORK.

RUNNING-BOARD SADDLE.

1,396,727.

Specification of Letters Patent. Patented Nov. 15, 1921.

Application filed July 29, 1921. Serial No. 488,283.

To all whom it may concern:

Be it known that I, GEARY E. CARSON, a citizen of the United States, and a resident of Albany, in the county of Albany and State of New York, have invented certain new and useful Improvements in Running-Board Saddles, of which the following is a specification.

The invention relates to improvements in running board saddles and more particularly to running board saddles having a metal saddle member. The main object of the invention is to provide a running board saddle which is not only strong and easily secured in place but also one which properly holds the running boards and is easy and cheap to manufacture and efficient in use. Further and more specific objects, features and advantages will more clearly appear from the detail description given below, taken in connection with the accompanying sheet of drawings which forms a part of this specification.

In the drawings Figure 1 is a plan view of a running board saddle showing running boards thereon and embodying the invention in a preferred form. Fig. 2 is a side view of parts shown in Fig. 1. Fig. 3 is a perspective of the metal saddle member shown in Figs. 1 and 2. Fig. 4 is a perspective of one of the end bearing blocks shown in Figs. 1 and 2. Fig. 5 is a perspective of the center bearing block shown in Figs. 1 and 2.

Referring to the drawings 6 represents a saddle member formed of pressed steel. The saddle member 6 has a flat top portion 7 provided with apertures or bolt holes 8 to accommodate bolts 9 for securing the running boards 10 on top of the saddle member, the bolts being counter sunk in the top of the running boards in order that there may be no projections extending above the top faces of the running boards which would likely trip the trainmen in walking along boards. The metal saddle member 6 is provided with struck up projections 11 at the ends thereof to prevent the running boards from slipping off the saddle member in case the bolts should for any reason become dislocated or the wooden boards split away therefrom. At each end the metal saddle member is bent downwardly as at 12 and outwardly laterally as at 13 to form depending portions which form end supports for the saddle member. Supporting

the lateral portions 13 are non-metallic bearing blocks 14 one at each end. The ends of the saddle member rest on these blocks which are preferably made of wood, and the blocks rest on the top of the cars 30 and prevent the saddle member from coming into engagement with the top of the car. If the metal saddle member rested directly on the metal roof of the car the vibration of the car would soon cause the saddle member to wear holes in the roof of the car. This is prevented by interposing the non-metallic bearing blocks 14. The lateral supporting portion 13 is provided with depending flanges 15 and 16 to aid in holding and protecting the bearing blocks 14. The blocks 14 are also preferably bolted to the lateral portions 13 by bolts 31. The flanges 16 of the end supporting portions of the saddle member are recessed as at 17 to accommodate and fit over the ridges 18 on the metal roof of the car. The blocks 14 are also recessed as at 19 to fit over and accommodate said ridges, which aid in holding the saddle in proper position on the car roof.

The saddle member 6 is also provided with integral lugs 20 bent down and depending from each side of the saddle member at the central part thereof and between the lugs 20 is located a central wood bearing block 21 resting on the top of the car and supporting the saddle member at the center thereof. The lugs 20 are recessed as at 22 and the block 21 is recessed as at 23 to accommodate and fit over the longitudinal central ridge on the top of the car. The block 21 is also recessed as at 24 to accommodate the ridges 18. The saddle is held firmly to the car roof by means of a central bolt 25, the head on the upper end of which sets in a depression 26 in the top flat face of the saddle member. The bolt passes centrally through the saddle member 6 and block 21 and down through the car roof and purlin being secured at its lower end by a nut 27. The saddle member is provided with integral depending flanges or ribs 28 extending along the sides thereof in order to strengthen the saddle member. The downwardly extending ends 12 are also provided with flanges 29 to strengthen the same. The whole saddle member 6 is so arranged that it may be easily and efficiently stamped out of sheet metal and yet is rigid and strong and requires a minimum amount of metal, and is extremely light in weight,

which are all considerations of importance. The arrangement has no metal parts extending above the upper faces of the running boards which would likely trip the trainmen walking over the boards. There are no nails or screws to become loose and work up through the boards and the use of the non-metallic bearing blocks 14 and 21 with the recesses therein makes the arrangement particularly advantageous for use on cars with metal roofs.

While I have described the invention in great detail and with respect to a preferred form thereof, I do not desire to be limited 15 to such details or form since many changes and modifications may be made and the invention embodied in widely different forms without departing from the spirit and scope thereof in its broader aspects as set forth 20 in the appended claims.

What I claim as new and desire to secure by Letters Patent, is:—

1. A running board saddle comprising a 25 pressed steel saddle member having a flat top surface for supporting the running boards and struck up projections at the ends of the saddle member, depending lugs on each side of the central part thereof, and depending portions of the respective ends 30 thereof, a bearing block held between said depending central lugs, and bearing blocks held in said depending end portions respectively.

2. A running board saddle comprising a 35 pressed steel saddle member having a flat top surface for supporting the running boards, and depending lugs on each side at the central part thereof, the ends of the member being bent downwardly and laterally to form end supports for the saddle 40 member.

3. A running board saddle comprising a 45 pressed steel saddle member having a flat top surface for supporting the running boards, and depending lugs on each side at the central part thereof, the ends of the member being bent downwardly and laterally to form end supports for the saddle member, the top of the member being also 50 provided with depending ribs or flanges to reinforce the same.

4. A running board saddle comprising a 55 pressed steel saddle member having a flat top surface for supporting the running boards, and depending lugs on each side at the central part thereof, the ends of the member being bent downwardly and laterally to form end supports for the saddle 60 member, the member being also provided with struck up projections at the ends thereof.

5. A running board saddle comprising a 65 pressed steel saddle member having a flat top surface for supporting the running

boards, and depending lugs on each side at the central part thereof, the ends of the member being bent downwardly and laterally to form end supports for the saddle member, and means for securing the saddle 70 to the top of a car at the center of the saddle member.

6. A running board saddle comprising a metal saddle member for supporting the running boards, a bearing block supporting 75 the central portion of the saddle member and bearing blocks supporting the end portions of the saddle member.

7. A running board saddle comprising a metal saddle member for supporting the 80 running boards, a bearing block supporting the central portion of the saddle member and bearing blocks supporting the end portions 85 of the saddle member, and means for securing the saddle to the top of a car at the central part of the saddle.

8. A running board saddle comprising a metal saddle member for supporting the running boards, a bearing block supporting 90 the central portion of the saddle member and bearing blocks supporting the end portions 95 of the saddle member, the saddle member having upwardly extending portions at the ends thereof to prevent the running boards from slipping off thereof.

9. A running board saddle comprising a metal saddle member for supporting the running boards, a bearing block supporting 100 the central portion of the saddle member and bearing blocks supporting the end portions of the saddle member, the saddle member having depending portions to aid in holding said bearing blocks in place.

10. A running board saddle comprising a metal saddle member for supporting the running boards, a bearing block supporting the central portion of the saddle member and bearing blocks supporting the end portions 105 of the saddle member, the saddle member being provided with apertures to accommodate bolts for bolting the running boards directly thereto and for holding the saddle to the top of a car.

11. A running board saddle comprising a 110 metal saddle member with a flat top part for supporting the running boards, the ends of the member being bent downwardly and laterally to form end supports for the saddle member, and the saddle member having 115 upwardly extending portions at the ends thereof to prevent the running boards slipping off thereof.

12. A running board saddle comprising a metal saddle member with a flat top part 120 for supporting the running boards, the member being bent downwardly and laterally to form end supports for the saddle member, the saddle member having upwardly extending portions at the ends there- 125 130

of to prevent the running boards slipping off thereof, and the top flat part of the saddle member being provided with bolt holes whereby the running boards may be

5 bolted thereto.

13. A running board saddle comprising a metal saddle member with a flat top part for supporting the running boards, the member being bent downwardly and laterally to form end supports for the saddle member, the saddle member having upwardly extending portions at the ends thereof to prevent the running boards slipping off thereof, and said end supports being recessed to accommodate the ridges in the roof of the car.

14. A running board saddle comprising a pressed steel saddle member having a flat top surface for supporting the running boards, and depending lugs on each side at the central part thereof, the ends of the member being bent downwardly and laterally to form end supports for the saddle member, and said depending lugs and end supports being recessed to accommodate the ridges in the roof of the car.

15. A running board saddle comprising a metal saddle member for supporting the running boards, a bearing block supporting the central portion of the saddle member and bearing blocks supporting the end portions of the saddle member, said bearing blocks being recessed to accommodate ridges in the roof of the car.

35 16. A running board saddle comprising a metal saddle member with a flat top part for supporting the running boards, the ends of the member being bent downwardly and laterally to form end supports for the saddle member, bearing blocks for supporting said end supports respectively and means

at each end of the saddle member for holding the bearing blocks in proper relation thereto.

17. A running board saddle comprising a 45 metal saddle member with a flat top part for supporting the running boards, the ends of the member being bent downwardly and laterally to form end supports for the saddle member, the saddle member being provided with depending side flanges for strengthening the same.

18. A running board saddle comprising a pressed steel saddle member, having a flat top part for supporting the running boards, 55 the ends of the member being bent downwardly and laterally to form end supports for the saddle member, and the member having bent up portions at the ends to prevent the running boards slipping off thereof. 60

19. A running board saddle comprising a pressed steel saddle member, having a flat top part for supporting the running boards, the ends of the member being bent downwardly and laterally to form end supports 65 for the saddle member, and wooden bearing blocks for supporting the ends of the saddle member to prevent the latter from engaging the roof of the car.

20. A running board saddle comprising a 70 pressed steel saddle member, having a flat top part for supporting the running boards, the ends of the member being bent downwardly and laterally to form end supports 75 for the saddle member, and non-metallic bearing blocks for supporting the ends and center of the saddle member to prevent the latter from engaging the roof of the car.

Signed at Albany, in the county of Albany and State of New York, this 27 day of 80 July, A. D. 1921.

GEARY E. CARSON.
